ELECTRIC SWITCH

Application filed August 29, 1921. Serial No. 496,260.

This invention is an electric switch and the object of the invention is to provide a switch for completing or breaking an electric circuit, which switch is in turn electrically operated, 5 in such manner that the making or completing of the electric circuit, which it controls is accomplished momentarily. In other words, the switch of the present invention is so constituted that when placed under 10 the influence of an electric current in one circuit, it will effect a momentary completion of another circuit, even though the first mentioned circuit continue to be energized.

Generally speaking, the present invention 15 embodies a switch having relatively movable contacts which are included in an electric circuit and the contacts are normally insulated from one another, but they are adapted to be momentarily brought into 20 electrical communication through the action of the movable core of a solenoid, so positioned that when the solenoid is operated, the overtravel of its core, due to the inertia of the initial impulse of current through 25 the solenoid coil will effect the electrical association of the contacts of the switch.

In one of its preferred, practical forms, the switch is so constructed that the core of the solenoid, during its overtravel, strikes the 30 pivot member which, in turn, effects the pressure of one contact against the other and by so doing completes the electrical circuit in which the switch is included. The solenoid is, however, so positioned that after 35 the initial impulse of current through the coil of the solenoid, said solenoid serves to retract the core into a balanced position and by so doing permits of the breaking of the circuit in which the switch is included.

40 In practice, the switch may be adapted for high efficiency by so constructing it that with each operation of the solenoid, the switch circuit may be completed a plurality of times, thus assuring an impulse of current 45 through the switch circuit.

Features of the invention, other than those specified, will be apparent from the hereinafter detailed description and claims, when read in conjunction with the accompanying 50 drawings.

The accompanying drawings illustrate different practical embodiments of the present invention, but the constructions therein shown are to be understood as illustrative, only, and not as defining the limits of the 55 invention.

Figure 1 is a front view of the preferred form of switch embodying the present invention; and,

Figures 2 and 3 diagrammatically show a 60 modified form of the switch.

Referring to the drawings, and more particularly to Figure 1, 1 designates a solenoid embodying the usual coil having a liner sleeve 2, in which a core, generally designated by the reference character 3, is mounted for reciprocation. The core 3 may be conveniently constructed of a rod 4 preferably of wood or insulating material and covered for a portion of its length with a tubular 70 sleeve 5 of soft iron. The liner 2 with the coil 1 thereon is rigidly supported in brackets 6 outstanding from the back plate 7, and at the lower portion of the back plate is an outstanding stop or foot 8, upon which the 75 lower end of the core is adapted to normally rest when the coil 1 of the solenoid is deenergized. Ordinarily, the solenoid stands in an upright position, so that the core thereof normally gravitates into engagement with the stop 8. The solenoid may be energized through any suitable electric circuit having leads 9 and 10 which include the coil of the solenoid in circuit.

Supported on the back plate 7 in the construction of Figure 1, is a pendulum 11, pivoted at 12 and provided at its lower end with a weight 13. The pivot 12 is preferably in the form of a screw which passes through the upper end of the pendulum and is normally fixed with respect to a metal plate 14, bolted or otherwise secured to a block of insulation 15, which is, in turn, fixed to the back plate 7. The pendulum 11 constitutes one contact of the switch and is included in an electric circuit of which the wire 16 constitutes one lead preferably by attaching the lead to the metallic plate 14 of a binding screw 17. The plate 14 and pendulum 11 being both metallic, as well as the screw 12, 100

the binding of the lead 16 to the plate will manifestly place the pendulum in electrical communication with the lead 16, though, in practice, this electrical communication may 5 be made more positive by clamping a metallic bracket 18 beneath the binding screw 17 and so constructing the bracket that it will reach over the pendulum, as shown in Figure 1. A light wire 19 may be secured at 10 one of its ends to the other end of the bracket 18 by a set screw 20, while the other end of this wire may be bound directly to the pendulum by a screw 21. In this way, a direct electrical connection is established between 15 the lead 16 and the pendulum 11.

The pendulum is adapted to normally gravitate into an upright, neutral position, wherein its lower end will lie substantially equidistant between the free ends of two 20 pivot arms 22 and 23. These two arms are pivoted to a metallic plate 24 by means of pivot screws 25 and the metallic plate 24 is, in turn, rigidly secured to a block of insulation 26, fixedly mounted on the back 25 plate 7. Springs 27 normally draw the arms 22 and 23 toward the pendulum 11 and into a position wherein their free ends will be adjacent the pendulum, though free from 30 engagement therewith, as shown in full lines in Figure 1.

The arms 22 and 23 taken with the plate 24, collectively, constitute, generally speaking, the other contact of the switch, when the pendulum 11 is considered as one contact. This second contact is included in the 35 electrical circuit to be controlled by attaching the other lead 16^a of said circuit to the plate 24 by a binding screw 28.

It will be apparent with this construction, 40 that so long as the pendulum 11 occupies a neutral position, the circuit of which the leads 16 and 16^a form a part, will be broken at the switch. It will be also apparent that if the pendulum 11 is swung in either direction to engage either of the arms 22 or 23 that a circuit will be established from the lead 16 to the lead 16^a or vice versa.

In accordance with the present invention, 45 this movement of the pendulum out of neutral position is accomplished by the core 3 of the solenoid which is adapted to engage with and operate upon an arm 29 formed integral or fixedly attached to the pendulum 11 adjacent its fulerum. As clearly shown 50 in Figure 1, the arm 29, as well as the pendulum 11, extend radially of the screw 12, and, in practice, the arm and pendulum are 55 preferably disposed at substantially right angles.

The parts are so associated that the free 60 end of the arm 29 is positioned directly above the upper end of the core 3 of the solenoid and at such distance thereabove that it will be free from engagement by the core both 65 when the core is in its normally depressed

and unenergized position, designated 3^a in Figure 1, and when the core is fully energized and at rest with current flowing through the solenoid, so that at these times, the switch circuit is normally broken.

I have found, however, that when current is passed through a solenoid provided with a core having weight, that the initial impulse of current through the core of the solenoid effects the movement of the solenoid 70 into a balanced condition, but before coming into such balanced condition, it overtravels the balanced position and thereafter retracts into the balanced position.

With this in mind, the parts are so relatively positioned that the core will, in its overtravel, strike the arm 29 and force it upwardly. By so doing, it is rotated through a greater or lesser angular travel about the axis of the screw 12 and through 80 such operation drives the pendulum 11 with considerable force against the pivot arm 22, and force the arm 22 back against the tension of the spring 27 associated therewith. By the time this has occurred, the core 3 85 has completed its overtravel and retracts into balanced position, whereupon the spring 27 acts to draw the arm 22 back into its normal position and in so doing throws the pendulum violently in a retrograde direction, 90 so that it engages with the arm 23 and forces it back against the tension of its spring 27. This back and forth swinging of the pendulum, causing it to alternately contact with the arms 22 and 23, and vice versa, will 95 continue until the force of the original impulse has been expended through flexing of the springs 27, but it will be apparent that each time the pendulum engages with either 100 of the arms 22 or 23, a circuit through the switch is completed and it will further appear that there will be a wiping action between the cylindrical weight of the pendulum and the arcuately shaped ends of the arms 22 and 23, which will keep the 105 contacting surfaces bright and free from corrosion, so that proper electrical contact may result. In order to guard against the arms 22 and 23 being thrown so far back as to place an undue strain on the springs 110 27, stops 30 are preferably provided, which 115 serve to limit the outward pivotal movement of said arms.

From what has been said with reference 120 to the construction of Figure 1, it is clear 120 that each time current is passed through the solenoid coil, a circuit, including the leads 16 and 16^a, will be positively completed at least once and it is found, in practice, that it is ordinarily completed by this construction two or three times any way. The advantage of this operation is that if the instruments, which may be included in the switch circuit, fail to operate on the first 125 impulse of current, they may be made to 130

operate on the second or third impulse, thereby assuring the operation of such instruments.

In practice, the solenoid as well as the other parts mounted on the face of the back plate 7, are preferably enclosed within a suitable casing, not shown.

In the constructions shown in Figure 1 of the drawings the part 11 is illustrated as a pendulum which is electrically connected with one of the leads 16 while the other lead 16^a is associated with the plate 24 which carries the pivoted contact arm 23. I wish it understood however that in practice a pair of contact arms may be used in lieu of each contact arm 23 and connected respectively to the leads 16 and 16^a so that when the pendulum swings it will engage both arms simultaneously at the termini of its swing and when so operating will act as a bridge piece to bridge said arms and complete the circuit. By arranging contact arms in pairs as described, I may control any number of circuits without positively including the pendulum but simply using said pendulum as a bridge piece.

I am further aware that since a pendulum is merely a weighted pivoted member, a circular disk weighted at one side with a projection like the ball-shaped end 13 will operate equally well except that its operation would necessarily be somewhat slower than the pendulum, due to the inertia or momentum of such disc which would operate after the manner of a fly wheel. The slower moving weighted disc might be employed to advantage if a relatively long momentary contact or closing of the electric circuit is desired. Since such a disc would operate more sluggishly than a pendulum.

In Figures 2 and 3 of the drawings, a modified form of arrangement is illustrated. In this modified form, the back plate 7^a has mounted thereon a solenoid 1^a, which may have a single winding or may have a double winding. That is to say, the solenoid 1^a, as well as the solenoid 1 of the present invention may be a single solenoid or two solenoids connected in series. The latter construction is shown in Figures 2 and 3. The leads of the solenoid 1^a are designated 9^a and 10^a and form a part of any desired operating circuit.

The solenoid 1^a is provided with a core 3, the same in all essential particulars as the core of the solenoid 1, and the lower end of the back plate has a stop 8^a, corresponding to the stop 8 for supporting the core of the solenoid when in depressed, idle position.

The switch of Figures 2 and 3 differs somewhat from the switch of Figure 1. It embodies a block of insulation 31, rigid with the back plate and preferably mounted within a casing 32, secured to the back plate by an angle bracket 33.

On the block of insulation 31 are secured two leaf springs 34 and 35, which normally extend in substantially parallel relation, though the spring 34 is longer and extends beyond the spring 35 and is bent to form a heel 36 adapted to bear against a rocker 37 pivoted at 38. The rocker carries a rigid arm 39 and the parts are so associated that when the leaf spring 34 bears against the rocker 37, it serves to normally hold the same in neutral position. The rocker may, however, be oscillated on its pivot 38 to bring the arm 39 into contact with the leaf spring 35. A binding screw 40 serves to bind one lead 16 of the switch circuit to the leaf spring 34, while the binding screw 41 serves to bind the other lead 16^a of the switch circuit to the spring 35.

In the normal position of the parts, the leaf spring 34 will bear against the rocker 37 and maintain the same in neutral position, but if the rocker is oscillated to bring the arm 39 into engagement with the spring 35, the switch circuit of which the leads 16 and 16^a form a part will be completed.

The parts are so arranged that the rocker will lie in the path of overtravel of the solenoid core 3 and a bumper 42 is preferably associated with the rocker to be engaged by the core when the solenoid 1^a is energized. When such energization takes place, the core 3 moves rapidly upward overtravels its balanced position and tilts the rocker, as shown in dotted lines in Figure 2, to complete the switch circuit, whereupon said core 3 immediately is retracted into the balanced position shown in Figure 3, thereby permitting of the immediate reopening of the switch.

The casing 32 may be provided with a suitable cover plate, thereby enclosing the leaf springs, though, in practice, I may enclose the entire device within a suitable casing.

The fundamental difference between the constructions of Figure 1 and that of Figures 2 and 3 is that each time the core of the solenoid is energized in the construction of Figure 1, the switch circuit will be rapidly made and broken a plurality of times, while in the construction of Figures 2 and 3, the switch will be closed only once for each operation of the solenoid.

In the construction of Figure 1, a single solenoid winding is illustrated, while in Figures 2 and 3, a duplex solenoid is shown, the windings of which are in series. I wish it understood that I may use these solenoid arrangements alternately in either construction, though I ordinarily prefer to use the duplex arrangement since greater movement of the core may be thus effected with a relatively small amount of current.

I am further aware that details of the switch described may be modified or va-

ried, as by the substitution of equivalents without departing from the present invention which is to be understood as broadly novel as is commensurate with the appended claims.

Having thus fully described the invention, what I claim as new and desire to secure by Letters Patent is:

1. In an assembly of the character described, a plurality of spaced contacts, normally insulated from one another, an operating member adapted when actuated to effect the completion of a circuit through the contacts, a solenoid provided with a movable core and positioned in such relationship to the operating member that when the solenoid is energized and the core magnetically held at rest, said core will be free from engagement with the operating member, means to permit the core to retract in a direction away from the operating member when the solenoid is de-energized and said operating member extending into the path of overtravel of the core, whereby when the solenoid is initially energized, the overtravel of the core will actuate the operating member to effect closing of the circuit.

2. In combination; a solenoid having a stationary coil and a movable core, said core being biased to an unattracted position with respect to said coil and said coil, upon energization, causing movement of said core from said unattracted position through its position of magnetic balance with respect to said coil to a point beyond and then back to its position of magnetic balance; and switch mechanism positioned to be operated by said core during said movement thereof when said core is beyond said position of magnetic balance.

3. In combination; a solenoid having a stationary coil and a movable core, said core being biased to an unattracted position with respect to said coil and said coil, upon energization, causing overtravel of said core and then the return thereof to a position of magnetic balance with respect to the coil; and switch mechanism positioned to be operated by said core upon overtravel thereof so that only a momentary operation of said switch mechanism is effected even though the energization of said coil is prolonged.

4. In an assembly of the character described, a solenoid having a stationary coil and a movable core adapted to normally partake of a retracted position, switch mechanism embodying a circuit closing member normally maintained in circuit breaking position, an operating member operatively connected with the circuit closing member and projecting into the path of overtravel of the core of the solenoid, whereby, when the solenoid coil is initially energized, the core will overtravel and en-

gage the operating member for the purpose of actuating the circuit closing member.

5. In an assembly of the character described, a solenoid having a stationary coil and a movable core adapted to normally partake of a retracted position, switch mechanism embodying a contact, a gravity contact member normally gravitating into neutral position with respect to said contact, an operating member associated with the gravity contact member and extending into the path of overtravel of the solenoid core, whereby, when the coil is initially energized, the overtravel of the core will actuate the operating member to effect movement of the gravity contact member into engagement with the contact.

6. In an assembly of the character described, a weighted member electrically connected with one lead of an electric circuit, a plurality of contacts positioned in the path of oscillation of the weighted member and so associated therewith that when the weighted member gravitates into normally neutral position, it will be free from engagement with the contacts, said contacts being electrically connected with the other lead of said circuit, an operating member operatively connected with the weighted member, and a solenoid provided with a movable core positioned in proximity with the operating member and in such relation thereto that the operating member will be in the path of overtravel of the core of the solenoid when the solenoid is initially energized, whereby the energizing of the solenoid will effect oscillation of the weighted member to engage said contacts in succession.

7. In an electric switch, a pendulum, a member mounted on the pivot of the pendulum and movable therewith with its free end arranged in the path of a movable core of a solenoid, two pivoted arms between which the lower end of the pendulum normally lies in neutral position, and a spring for each arm arranged to act thereon to normally hold the free ends of said arms toward each other, said arms being movable outward or away from each other by contact of the end of the pendulum therewith, said pendulum and the arms being of conductive material to permit the feed of electrical current therethrough when the pendulum contacts with said arms.

In testimony whereof I have signed the foregoing specification.

FRANZ A. BOEDTCHER.
